OIL WELL RACK DEVICE

Robert O. Laird, Cement, Okla., and Needum
W. Friddle, Kellerville, Tex.

Application November 7, 1940, Serial No. 364,736

5 Claims. (Cl. 211—60)

This invention relates to an oil well rack device, and has for the primary object the provision of a device of the above stated character which may be easily installed on an oil well derrick as a safety device to prevent falling of well tubing or casings arranged in standing position on the derrick floor awaiting use, and is so constructed to accommodate a varying number of tubes or casings to each stack and a varying number of stacked tubes or casings and may be easily adjusted when desired either for the uses specified or for transportation without danger of damage thereto.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawings, in which—

Figure 1 is a fragmentary side elevation illustrating a portion of an oil well derrick construction showing the present invention adapted thereto for a safety medium in the retaining of oil well tubes or casings stacked on end upon the floor of the derrick construction.

Figure 2 is a top plan view illustrating the device.

Figure 3 is a fragmentary top plan view, partly in section, and drawn on an enlarged scale illustrating the means of adjusting the present invention.

Figure 4 is a transverse sectional view taken on the line 4—4 of Figure 2.

Figure 5 is a perspective view illustrating one of the adjusting bars.

Figure 6 is a fragmentary perspective view illustrating one of the restraining rods.

Referring in detail to the drawings, the numeral 5 indicates a fragmentary portion of a well derrick construction, the flooring being indicated by the character 6. It is the customary practice to stack on the floor 6 in standing position well tubes or casings 7 when awaiting use. As such devices are of considerable weight there is always danger when left standing of falling and injuring the construction of the device as well as the operators of the well. To prevent accidents the present invention is devised and is readily adaptable to the derrick construction 5 at a selected distance above the floor 6 so that the well tubes or casings will be restrained adjacent their upper ends from falling over or 55

moving out of standing position. However, the construction of the present invention is such that the well tubes or casings can be readily removed for use at any time desired.

5 A substantially rectangular shaped frame 8 is provided with end apertured pieces 9 to receive bolts or like fasteners for the mounting of the frame on the derrick frame construction. One of the side members indicated by the character 10 of the frame 8 is provided with spaced slots 11 through which may slide restraining rods or fingers 12. The end members of the frame are provided with slots 13 to slidably receive the ends of a shaft 14. The inner ends of the fingers 12 are provided with T-shaped sleeves 15 journaled on the shaft 14. By having the fingers 12 slide in the slots 11 and journaled on the shaft 14 will permit any one of the fingers or any number of said fingers to be swung upwardly and rearwardly to an inoperative position, also extended or retracted with respect to the frame. Also the shaft 14 being slidable in the slots 13 permits the fingers to be retracted substantially within the frame so that the device 15 can be shipped without danger of damage to other devices or injury to the fingers.

Also, the shaft 14 slidable in the slots 13 will permit the operator to advance the fingers various distances outwardly of one side of the frame 10 to form spaces therebetween for the accommodation of varying numbers of well casings or tubes arranged on end as shown in Figure 1.

Operating shafts 16 are journaled in the end members of the frame 8 and have formed on ends 35 thereof crank handles 17 whereby said shafts may be rotated in opposite directions. Crank arms 18 are secured on the operating shafts and have pivoted thereto ratchet bars 19 provided with teeth 20 to engage with the shaft 14. The 40 ratchet bars 19 are arranged in pairs with the pairs of ratchet bars opposing each other and engaging the shaft 14 so that on the operation of one of the shafts 16 the shaft 14 will be slid in one direction in a step by step motion and 45 when the other operating shaft 16 is actuated the rack bars thereof will slide the shaft 14 in a reverse direction in a step by step movement.

It is to be understood that when the shaft 14 50 is being slid in one direction by one pair of ratchet bars the other pair of ratchet bars are disengaged from the shaft 14 and supported in a partially elevated position. In order that the pairs of rack bars may be elevated as specified, operating shafts 20 are journaled in the frame

and are provided with handles 21 and have integral therewith plates 22 underlying the ratchet bars so that on operation of the shafts 20 the ratchet bars may be elevated out of engagement with the shaft 14. This construction permits any of said pairs of ratchet bars to be disengaged from the shaft 14 when desired.

Surrounding the operating shafts 16 are coil springs 24 having certain ends thereof secured to the frame, as shown at 25, while the opposite ends bear against the crank arms 18 for the purpose of urging the operating shafts 16 in the direction of bringing the ratchet bars 19 in engagement with the shaft 14.

A restraining rod 28 is slidably mounted in key-shaped openings provided in the end members of the frame. The restraining rod 28 has a pin 29 which when moved in a vertical position will permit the restraining rod to be slid endwise for the purpose of moving from over the fingers. Any number of the fingers 12 may be uncovered by the restraining rod so that they can be swung into an inoperative position if desired.

A restraining rod, similar to the restraining rod 28, is indicated by the character 30 and is slidably mounted in the frame to overlie the ratchet bars. This rod is provided with pins 31 which must be positioned in a certain way to pass through the keyhole slots of the frame. When said shaft 14 is engaged by both pairs of ratchet bars, the shaft then cannot slide in a slot 13 in either direction consequently the fingers are secured in an adjusted position either extended or retracted with respect to the frame. The rod 30 must be removed from the frame 35 along with the rod 28 when it is desired to position the fingers in inoperative position.

A safety chain 34 may have its ends detachably connected to hooks 35 formed on the frame. The safety chain may be brought about the groups of stacked well tubes or casings between the fingers and prevent them from being moved outwardly from said fingers. The safety chain is preferably employed only when the well is left unattended or overnight.

While we have shown and described the preferred embodiment of our invention, it will be understood that minor changes in construction, combination and arrangement of parts may be made without departing from the spirit and scope 50 of the invention as claimed.

Having thus described the invention, what we claim is:

1. In a well derrick rack, a frame, a shaft mounted on said frame for sliding movement toward and from one side of the frame, fingers carried by said shaft and slidably engaging said frame and adapted to extend outwardly from said side of the frame to define spaces for the accommodation of a plurality of well tubes arranged on end, and means for imparting sliding

movement to said shaft in either direction to extend or retract the fingers.

2. In a well derrick rack, a frame, a shaft mounted on said frame for sliding movement toward and from one side of the frame, fingers carried by said shaft and slidably engaging said frame and adapted to extend outwardly from said side of the frame to define spaces for the accommodation of a plurality of well tubes arranged on end, operating rods journaled in said frame and including handles, crank arms secured to said rods, ratchet bars journaled on said crank arms and in engagement with said shaft and arranged in pairs with the pairs of ratchet bars disposed in opposed relation.

3. In a well derrick rack, a frame, a shaft mounted on said frame for sliding movement toward and from one side of the frame, fingers carried by said shaft and slidably engaging said frame and adapted to extend outwardly from said side of the frame to define spaces for the accommodation of a plurality of well tubes arranged on end, operating rods journaled in said frame and including handles, crank arms secured to said rods, ratchet bars journaled on said crank arms and in engagement with said shaft and arranged in pairs with the pairs of ratchet bars disposed in opposed relation, means on said frame whereby either pair of ratchet bars may be elevated out of engagement with said shaft.

4. In a well derrick rack, a frame, a shaft mounted on said frame for sliding movement toward and from one side of the frame, fingers carried by said shaft and slidably engaging said frame to extend outwardly from said side of the frame to define spaces for the accommodation of a plurality of well tubes arranged on end, operating rods journaled in said frame and including handles, crank arms secured to said rods, ratchet bars journaled on said crank arms and in engagement with said shaft and arranged in pairs with the pairs of ratchet bars disposed in opposed relation, means on said frame whereby either pair of ratchet bars may be elevated out of engagement with said shaft, springs carried by said operating rods and acting on said crank arms to urge the ratchet bars into engagement with said shaft.

5. In a device of the character described, a demountable frame, a shaft mounted on said frame for sliding movement toward and from one side of the frame, fingers journaled on said shaft, said frame having slots to slidably receive said fingers, a ratchet means for sliding the shaft in opposite directions to extend and retract the fingers, and restraining means carried by said frame for the fingers and capable of releasing one or more of said fingers to permit them to be swung into inoperative position.
